(74) Attorney, Agent, or Firm — Locke Lord LLP; Tim
Tingkang Xia, Esq.

(57) **CLAIM**

The ornamental design for a handle connector, as shown and
described.

DESCRIPTION

FIG. 1 is a top front right perspective view showing first
embodiment of my new design;

FIG. 2 is a top front left perspective view thereof;

FIG. 3 is a bottom rear left perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is a front view thereof with a mobile computer.
The broken lines are directed to environment and are for
illustrative purposes only. The broken lines form no part of
the claimed design.
